UNITED STATES PATENT OFFICE.

GEORGE E. A. HALLETT, OF DAYTON, OHIO, ASSIGNOR TO GENERAL MOTORS RESEARCH CORPORATION, OF DAYTON, OHIO, A CORPORATION OF DELAWARE.

AIR-COOLED ENGINE.

Application filed March 14, 1925. Serial No. 15,654.

This invention relates to air-cooled internal-combustion engines, and particularly to automotive vehicles propelled by such engines.

- 5 One of the objects of the present invention is to provide for the removal from the engine hood of the warm air which is expelled by the air-circulating fan during the operation of the engine.
- 10 Further objects and advantages of the present invention will be apparent from the following description, reference being had to the accompanying drawings, wherein a preferred form of the present invention is
- 15 clearly shown.

In the drawings:

Fig. 1 shows partly in side elevation and partly in section, an internal-combustion engine and cooling system therefor.

- 20 Fig. 2 is a sectional view on the line 2—2 of Fig. 1.

Referring to the drawings, 20 designates an internal-combustion engine provided with a crankcase 21, a plurality of cylinders 22 each having heat-dissipating fins 23. These fins are surrounded by a draft-tube skirt 24 communicated with the draft-tube manifold 25 having an outlet at 26 to the inlet of a peripheral discharge fan 27. Fan 27 is mounted between the rear cylinder of the engine and the vehicle dashboard 28 upon a shaft 29 supported by a bracket 30 closing the front end of the draft-tube manifold 25 and by a bracket 31 provided with openings 31^a permitting the passage of warm air from the manifold 25 to the fan 27. The shaft 29 carries a pulley 32 connected by a belt 33 with a pulley 34 attached to the shaft 35 of the engine.

- 40 The enclosure for the engine includes a hood having a front portion 40 having louvers 41 which tend to direct the air entering the hood upwardly, and having hinged side sections 42, 43, 44 and 45, extending from the front portion 40 to the dashboard 28 of the vehicle. The bottom of the enclosure is completed by two plates 46 each extending from one of the side channels 47 of the vehicle frame to the crankcase and from

the front cross-channel member 48 of the vehicle frame toward the rear of the engine. Each plate includes a downwardly-inclined portion 46^a terminating with an edge 46^b spaced from the housing 49 of the engine flywheel 50.

The warm air which is discharged from the fan tends to move from the fan in a direction at right angles to the fan shaft 29 until it impinges upon the sides of the hood. Then this warm air tends to spread out especially where the fan is close to the hood. When the vehicle is in motion, the air entering through the louvers 41 tends to move in the direction of the arrows 51 and counteracts to some extent the spreading of the warm air discharged by the fan toward the engine cylinders, and tends to maintain this fan discharge in a zone adjacent the dashboard 28 and the flywheel housing 49. Arrows 52 in Fig. 2, and 53 and 54 in Fig. 1, indicate the general direction of air discharge from the fan. Arrow 54 indicates that some of the air tends to flow parallel to the toe-board 55, but the general direction of air flow is in the direction of arrow 53.

The velocity of the air leaving the fan is not very great due to maintaining at a low value the power required to operate the fan. Therefore, means are provided for using the currents of air due to the motion of the vehicle for withdrawing the heated air from the region of fan discharge. This means includes the pans 46 and their air-deflecting portions 46^a. During the motion of the vehicle the air following the underside of the plates 46 in the direction of arrow 56 will be deflected in the direction of arrow 57. The deflection of this current of air tends to produce a region of low pressure adjacent the flywheel housing 49, and consequently the fan discharge is drawn toward the air current indicated by arrow 57.

In some installations it may be necessary to provide additional means for preventing any of the fan discharge mingling with the cooler air entering the engine draft tube 24. This means can be a partition 60 extending from the sides of the engine crankcase draft

tube and draft-tube manifold, to the sides of the hood, and from the top of the hood to an edge 61 on each side of the engine and spaced from the air deflector 46^a in order to allow 5 the air entering the hood to pass out of the hood and be drawn into the air stream indicated by arrow 57. The partition 60 carries a baffle 62 surrounding the draft tube 24 at the rear side of the rear cylinder. The 10 partition 60 and baffle 62 are not always necessary, especially where the air discharged from the fan can readily pass around the engine frame.

While the form of embodiment of the 15 invention as herein disclosed, constitutes a preferred form, it is to be understood that other forms might be adopted, all coming within the scope of the claims which follow.

What is claimed is as follows:

20 1. In an automotive vehicle comprising a frame and an engine carried adjacent the front end of the frame, a hood enclosing the front, top and sides of the engine, dash and toe boards enclosing the rear of the engine, air-cooling means for the engine including a fan located adjacent the dashboard and above the engine flywheel at the rear of the engine, and means for causing currents of air created outside the engine 25 hood by the motion of the vehicle to draw out from the engine enclosure the warm air discharged by the fan.

30 2. In an automotive vehicle comprising a frame and an engine carried adjacent the front end of the frame, a hood enclosing the front, top and sides of the engine, dash and toe boards enclosing the rear of the engine, air-cooling means for the engine including a fan located adjacent the dashboard and above the engine flywheel at the rear of the engine, and an air deflector located in the path of the air current produced adjacent the bottom of the engine by the motion of the vehicle, for causing said 35 air current to be deflected downwardly adjacent the rear of the engine whereby to cause the warm air discharged by the fan at the rear of the vehicle to be withdrawn from the engine enclosure.

40 3. In an automotive vehicle comprising a frame and an engine carried adjacent the front end of the frame, a hood enclosing the front, top and sides of the engine, dash and toe boards enclosing the rear of the engine, air-cooling means for the engine including a fan located adjacent the dashboard and above the engine flywheel at the rear of the engine, and means tending to prevent the warm air discharged from the 45 fan coming in contact with the engine cylinders.

45 4. In an automotive vehicle comprising a frame and an engine carried adjacent the front end of the frame, a hood enclosing the front, top and sides of the engine, dash and

50 toe boards enclosing the rear of the engine, air-cooling means for the engine including a draft tube surrounding the side walls of the cylinders, a draft-tube manifold and a fan located at the rear end of the manifold and adjacent the dashboard, and means tending to prevent the warm air discharged by the fan from entering the draft tube.

55 5. In an automotive vehicle comprising a frame and an engine carried adjacent the front end of the frame, a hood enclosing the front, top and sides of the engine, dash and toe boards enclosing the rear of the engine, air-cooling means for the engine including a draft tube surrounding the side walls of the cylinders, a draft-tube manifold and a fan located at the rear end of the manifold and adjacent the dashboard, means including louvers located at openings in the front 60 of the hood, and inclined upwardly toward the rear of the vehicle for preventing the warm air discharged by the fan from entering the draft tube.

65 6. In an automotive vehicle comprising a frame and an engine carried adjacent the front end of the frame, a hood enclosing the front, top and sides of the engine, dash and toe boards enclosing the rear of the engine, air-cooling means for the engine including a fan located adjacent the dashboard and above the engine flywheel at the rear of the engine, means tending to maintain the air discharged from the fan in a region adjacent the rear of the engine, and means dependent on air currents produced outside the engine hood during the motion of the vehicle for withdrawing the fan discharge 70 from the engine enclosure.

70 7. In an automotive vehicle comprising a frame and an engine carried adjacent the front end of the frame, a hood enclosing the front, top and sides of the engine, dash and toe boards enclosing the rear of the engine, air-cooling means for the engine including a draft tube surrounding the side walls of the cylinders, a draft-tube manifold and a fan located at the rear end of the manifold and adjacent the dashboard, for producing a circulation of air upwardly through the draft tube and outwardly from the fan, and means for utilizing air currents produced by the motion of the vehicle for withdrawing from the engine enclosure the heated air 75 discharged from the fan.

75 8. In an automotive vehicle comprising a frame and an engine carried adjacent the front end of the frame, a hood enclosing the front, top and sides of the engine, dash and toe boards enclosing the rear of the engine, air-cooling means for the engine including a fan located adjacent the dashboard and above the engine flywheel at the rear of the engine, and means for causing the air discharged by the fan to be circulated downwardly around the flywheel.

9. In an automotive vehicle comprising a frame and an engine carried by the frame, means for circulating air adjacent the engine cylinders including an engine operated fan, 5 positioned above the engine flywheel and an enclosure for the fan preventing the warm air discharged by the fan coming in con-

tact with the engine cylinders, said enclosure being open at the bottom and rearwardly of the cylinders. 10

In testimony whereof I hereto affix my signature.

GEO. E. A. HALLETT.
